G. P. HERRICK.
LENS MOUNTING.
APPLICATION FILED AUG. 21, 1917.

1,317,131.

Patented Sept. 23, 1919.

UNITED STATES PATENT OFFICE.

GERARDUS POST HERRICK, OF NEW YORK, N. Y.

LENS-MOUNTING.

1,317,131.

Specification of Letters Patent. Patented Sept. 23, 1919.

Application filed August 21, 1917. Serial No. 187,326.

To all whom it may concern:

Be it known that I, GERARDUS POST HERRICK, a citizen of the United States, residing at New York city, borough of Manhattan, 5 in the city of New York and State of New York, have invented certain new and useful Improvements in Lens-Mountings, of which the following is a specification.

My invention relates broadly and generally 10 to new and useful improvements in lens mountings, by means of which a lens or glass is connected to a supporting member, and more particularly to that character or type of mounting adapted to secure an eye-glass 15 lens or glass to the bridge or nose piece of eye-glasses.

The invention consists in the improvements to be more fully described hereinafter and the novelty of which will be particularly 20 pointed out and distinctly claimed.

I have fully and clearly illustrated my invention in the several figures of the accompanying drawings to be taken as a part of this specification and wherein—

25 Figure 1 is an enlarged view in elevation of a portion of an eye-glass bridge-piece and the support for connecting the lens or glass thereto.

Fig. 2 is a left side elevation of Fig. 1, 30 with the bridge-piece removed and the support being shown partly in section.

Fig. 3 is an enlarged elevation of the supporting member illustrated in Figs. 1 and 2.

Fig. 4 is a longitudinal section view 35 through the embodiment shown in Fig. 1.

Fig. 5 is an enlarged view partly in section and in edge elevation of another embodiment of the same invention.

Fig. 6 is a longitudinal section through 40 the form shown in Fig. 5.

Fig. 7 is a view similar to Fig. 5 but showing another arrangement of securing the lens holding element in position on the supporting member.

45 Fig. 8 is an enlarged elevation of another embodiment of the same invention.

Fig. 9 is a side elevation of the mounting shown in Fig. 8 applied to a lens or glass.

Fig. 10 is an enlarged front elevation of a 50 still further embodiment.

Fig. 11 is a side elevation of the embodiment shown in Fig. 10 applied to a lens or glass.

Fig. 12 is a sectional view of a modified

form of the invention showing a simplified 55 method of forming the wire holding passages therein.

Fig. 13 is a plan view of a packing member.

Fig. 14 is a longitudinal central section 60 of the packing member of Fig. 13, and

Fig. 15 is a transverse section thereof.

Referring to the drawings by characters of reference, and particularly Figs. 1, 2, 3 and 4, 1 designates a portion of a bridge-piece of a well-known type commonly employed in pince-nez eye-glasses, the same supporting or having connected thereto a nose grip member 2. These elements specifically form no part of my invention and need 70 not be further illustrated or described, as it will be understood that the invention is not to be limited to use in connection with any particular form of bridge-piece or nose-piece. 75

3 designates a lens or glass supporting member preferably consisting of a post or lug 4 having a channeled attaching head 5, the groove 5^a of which receives the spring or bridge-piece and the side portion of the 80 nose-piece 2, and to which lug the nose-piece is secured by a clamping screw 6 extending through the nose-piece and threaded longitudinally into a socket 7 in the lug, as indicated in Fig. 4 of the drawings. Carried by the lug 4 is a curved member 8 which may include oppositely disposed arms or members 9, 10, extending respectively in opposite directions from the said lug or post 4. 85

The curved member 8 is curved or otherwise 90 formed on one face as at 8^a to conform to the peripheral contour of a lens or glass 11, so that when the said member is in assembled relation to the lens, a close fit or joint between the two is afforded. The lens or glass 95 is provided with a circumferential edge groove 12 adapted to receive a flexible wire 13, the ends of which are connected to the member 8 to secure the lens to the mounting.

I will now describe the novel construction 100 of the supporting member and the improved manner of connecting said wire 13 thereto, as illustrated in Figs. 1, 2, 3 and 4 in order to hold the lens rigidly and securely in engagement with said supporting member. One end of the member 8, that is, that part 105 constituted by the arm 9, is provided with two openings 14, 15 spaced apart from

each other lengthwise of the said arm 8, which openings, are preferably arranged with their longitudinal axis parallel to each other and extending from the face 8^a to the back of the member 8, and are adapted to receive one end of the wire 13 to anchor the latter securely to the supporting member. In order to accomplish this result the end portion of the wire preferably passes between the said member 8 and the lens or glass and is passed through the opening 14, from the face 8^a, the wire being sharply kinked or bent at the point at which it enters said opening, as clearly indicated at 16. On the outer face of the member 8 the wire is bent or sharply kinked as at 17 and laid flat upon said outer face, and is bent or kinked as at 18 and inserted in the said opening 15. The manner of anchoring the end of the wire as just described provides an efficient means for securing the wire to the supporting member when the wire is placed under tension as hereinafter described, but I do not desire to be limited to this particular anchorage as other methods may be employed without departing from my invention. The back of the member 8 may be provided with a groove 14^a (see Fig. 3) joining the outlets to the openings 14, 15, and adapted to receive the wire, so as to provide a seat for the latter, and afford a slight arrangement.

At the opposite end from that just described, the member 8 is provided with an end passage preferably in the form of a notch or recess 19 opening at one end through the end of the arm 10 as indicated at 20, said notch extending longitudinally of the member 10 and preferably extending entirely through the same from the face 8^a, to the back of said member. The rear end of the notch opens into a groove 21 extending longitudinally of the arm 10, and preferably from the rear end of said notch to the post 4 heretofore described. The post 4 is provided with a transverse opening 22, both ends of which are exposed or accessible for a purpose to be presently described, and which opening is preferably disposed with its longitudinal axis in line or substantially in line with the longitudinal axis of the groove 21 heretofore described. The opening 22 is preferably arranged so that its longitudinal axis is as near as possible in a straight line with the general longitudinal direction of the groove 21, that is, it is preferably substantially tangential to the bottom of the groove in the lens, so as to facilitate threading of the wire through said opening, and preventing such bending or kinking at the inlet end of the opening as might render it difficult to properly tension the said wire by pulling it through said opening. When the lens or glass is to be secured in position against the mount or supporting member 8,

the wire 13 is first anchored to the arm 9 in a suitable manner, for instance, as above described, and is then passed about the lens in the groove 12, and the opposite end portion located in the notch or slot 19 and groove 21, and is then passed through the opening 22 and pulled until said wire is placed under sufficient tension to hold the lens snugly and firmly against the face 8^a of the member 8, whereupon the end of the wire which emerges from the outlet end of the opening 22, that is, the end on the opposite side of the post from the arm 10, is bent over or sharply kinked as at 23, whereby the wire is held in position and its holding tension maintained.

In the form shown in Figs. 1, 2, 3 and 4 the mount is preferably provided with a second opening 24 extending through the mount at an angle to the opening 22, both ends of said second opening being exposed so that the free end of the wire may be inserted through the same when the lens is in place, and the end of the wire pulled through the same so that an additional anchorage or lock is provided to insure the holding tension of the wire being maintained. As clearly indicated in Fig. 2 in passing the free end of the wire through the opening 24, the wire is again kinked as at 25 so that the said wire is provided with two locking kinks which act to securely hold the wire.

It will be noted that the notch 19 and the groove 21 provide a seat or guide for the wire so that the latter will not become dislodged by lateral movement from the arm 10, and which arrangement has the further advantage that it enhances the sightliness of the mount, inasmuch as the wire does not simply bridge or lie upon the surface of the mount, as would be the case were said notch and groove omitted.

In Figs. 5 and 6, I have shown another manner of anchoring the end of the wire to the arm 9, which consists in providing said arm with an end notch 26 leading to a longitudinal groove 27, the inner end of which terminates in a transverse opening 28, said arm being also provided between said opening 28 and the post or lug 4, with a second opening 29. In this form of the invention, the wire 13 passes from the lens through the notch or passage 26 and groove 27 to the said opening 28, at which point, and on the back of the mount it is kinked as at 28^a and passed through said opening in the direction of the lens, and is then again kinked at the inner end of the opening 28, as indicated at 28^b and carried lengthwise of the mount on the under-face thereof to the opening 29, whereupon it is again kinked at 29^a and passed outward through said opening. In this form shown in Fig. 5, the arm 10 of the mount 8 may be, and preferably is, of

the construction shown and described with reference to Figs. 1, 2 and 3, and the lug 4 is also provided with an opening 22, but the opening 24 may be omitted if desired, 5 and the end of the wire located and held by wrapping it around the post or lug 4 as indicated at 31, and securing the end by inserting it under the wire 13, that is, between it and the member 10, at the point where the 10 wire enters the said opening 22.

In Fig. 7 the construction of the mount as regards the supporting member 8, and the lug 22 is the same as that shown in Figs. 5 and 6, but a simple form of securing the extreme end of the wire is shown, which consists in merely bending the same to conform to the contour of the post. This method of arranging the end of the wire is not as secure as in the forms hitherto described, in 15 the sense that said end is not held or located against such accidental bending movement as might result in the derangement of the lugging kink 23, but aside from accidental displacement the arrangement shown will 20 efficiently hold the end of the wire in such manner as to maintain the tension on the wire.

In the form shown in Figs. 8 and 9, the supporting member may consist of the post 30 4 upon a member with only one extension adapted to engage the edge of the lens, said extension being shown at 9^a and being provided, in the same manner as described with reference to Figs. 1 to 4 inclusive, with openings 14, 15, to receive and anchor the fixed end of the wire 13. In this form of the invention the opening through the mount which is adapted to receive the end of the wire upon which the pull is exerted, is indicated at 22^a and extends through the mount and post 4 in an inclined direction and with its longitudinal axis substantially tangential to the circumference of the lens. In this form of the invention the post or mount is 45 also provided with a second opening 24^a, the wire being kinked at the point at which it emerges from the outlet end of the opening 22^a, as indicated at 23^a and then being bent around the post and again kinked as 50 at 25^a and inserted through the said opening 24^a.

In Figs. 10 and 11 the supporting member 8 may include two arms 9, 10 as described with reference to Figs. 1 to 7 inclusive, and the construction of the arm 9 may be of either of the forms previously described, but the arm 10 is not notched or grooved. In this form the end of the wire passes under the arm 10 and through an inclined opening 21^a, the inlet end of which is located between the member 8 and the edge of the lens, and the outlet end of which is on the side of the post 4 opposite to said arm 10, said opening being in longitudinal 60 alignment with the groove 12 in the lens, and

substantially tangential to the circumference of the latter. In this form of the invention the post is also provided with a transverse locking opening 29^b to receive the extreme end of the wire after the same has 70 been kinked in substantially the manner as described with reference to Figs. 1 to 4 inclusive and 8 and 9.

In Fig. 12 I have shown a simplified manner of forming the passages for the wire, 75 the passages being constituted by channels 22^b and 24^b, said channels being formed from the under-side of the supporting member in such manner that the inner end of the channel 22^b projects into the post 4 beyond the outer surface of the members 9, 10, a sufficient distance to form a transverse passage through the post, as indicated at 22^c, while the transverse channel or groove 24^b opens adjacent the edge of the lens and 85 forms a passage at right-angles to the passage 22^c.

In Figs. 1, 4, 6, 9, 11 and 12 is shown a packing member 30 inserted between the inner face of the supporting member and the adjacent edge of the lens. This packing member is illustrated in Figs. 13, 14 and 15, and consists preferably of a wedge member which preferably tapers longitudinally and in which the side edges are also 95 inclined toward each other so as to make the member narrower at one end than at the other. The said packing member also is preferably beveled from its longitudinal median line in opposite directions toward its side edges, as indicated in Fig. 15. The packing member is preferably applied after the lens has been secured against the mounting by exerting tension on the wire. The lens may be strained from the mounting 100 in the direction of its own plane and the wedge inserted small end first, between the edge of the lens and the under adjacent face of the mounting and as it is pulled through its tensioning effect increases until the desired rigidity is reached. The use of this wedge may be found desirable where necessary to increase rigidity, but may be omitted where the desired rigidity is obtained by merely tensioning the wire. 110 After locating the strip 30 between the lens and the mounting, the ends of the strip are cut off flush with the side faces of the lens and the mount. The packing member is preferably made of celluloid or other 120 flexible material which will conform to the edge of the lens and the mount, so as not to detract from the appearance.

It will be noted that in all the forms described, the wire passes through an opening in the mount, of which the pulled end is accessible to the operator so that the end of the wire, after the latter has been threaded through said opening, may be grasped and pulled in order to tension the wire 130

after the lens is in place and then bent laterally so as to be kinked to maintain the wire tension.

What I claim and desire to secure by Letters Patent of the United States is—

1. In a device of the character described, a lens having a circumferential edge groove, a support for the lens, said support having a projecting post, a wire passing around the lens and seated in said groove, and having one end anchored to said support, and a fastening securing the other end of said wire to said support, said fastening including an opening through said support together with additional means on the post for securing said other end of said wire directly to said projecting post. 10
2. In a device of the character described, a lens having a circumferential edge groove, a support for the lens, said support having a projecting post, a wire passing around the lens and seated in said groove, and having one end anchored to said support, and a fastening securing the other end of said wire to said support, said fastening including an opening through said support, and an opening through said post, through which openings said other end of the wire is passed. 15
3. In a device of the character described, a lens having a circumferential edge groove, a support for the lens, said support having a post, a wire passing around the lens and seated in said groove, and having one end anchored to said support, and a fastening securing the other end of said wire to said support, said fastening including an opening through said post through which said other end of said wire is passed and secured. 20
4. In a device of the character described, a lens having a circumferential edge groove, a support for the lens, said support having a post having a hole therethrough, a wire passing around the lens and seated in said groove having one end anchored to said support, and the opposite end passed through said hole and bent at an angle at the outlet end of said hole. 25
5. In a device of the character described, a lens having a circumferential edge groove, an integral support for the lens, said support including a member adapted to lie against the lens and a second member at an angle to the first named member, a wire passing around the lens and seated in said groove and having one end anchored to said support, and a fastening securing the other end of said wire to said support, said fastening including an opening through said second member through which opening said other end of said wire is passed and secured. 30
6. In a device of the character described, a lens having a circumferential edge groove, 65
- a support for the lens, said support having a post, a wire passing around the lens and seated in said groove and having one end anchored to said support, and a fastening securing the other end of said wire to said support, said fastening including an opening through said post through which openings said other end of said wire is passed and secured. 70
7. In a device of the character described, a lens having a circumferential edge groove, a support for the lens, said support having a post, a wire passing around the lens and seated in said groove and having one end anchored to said support, and a fastening securing the other end of said wire to said support, said fastening including an opening through said post through which openings said other end of said wire is passed and secured, both ends of said opening being accessible when the lens is in assembled relation to the support. 75
8. In a device of the character described, a lens having a circumferential edge groove, a support for the lens, said support having a post, a wire passing around the lens and seated in said groove and having one end anchored to said support, and a fastening securing the other end of said wire to said support, said fastening including an opening through said post through which openings said other end of said wire is passed and secured, both ends of said opening being exposed when the lens is in assembled relation to the support, and a second hole through the said post and adapted to receive the end of the wire after it has been passed through the first named hole. 80
9. In a device of the character described, a lens having a circumferential edge groove, a support for the lens, said support having a post, a wire passing around the lens and seated in said groove and having one end anchored to said support, and a fastening securing the other end of said wire to said support, said fastening including an opening through said post through which openings said other end of said wire is passed and secured, both ends of said opening being exposed when the lens is in assembled relation to the support, and a second hole through the said post and adapted to receive the end of the wire after it has been passed through the first named hole, said second hole being arranged with its axis at an angle to the axis of the first named hole. 85
10. In a device of the character described, a lens having a circumferential edge groove, a support for the lens, said support having a post and also formed with a groove, a wire passing around the lens and seated in the groove in the lens, and having one end anchored to said support, and a fastening securing the other end of the wire to said support, said fastening including an opening through said post, said other end of said wire being seated in said groove in the support and threaded through said opening in the post and recessed. 90
11. In a device of the character described, a lens having a circumferential edge groove, a support for the lens, said support having a post having a hole therethrough, a wire passing around the lens and seated in said groove and having one end anchored to said support, and the opposite end passed through said hole. 95
12. In a device of the character described, a lens having a circumferential edge groove, a support for the lens, said support having a post having a hole therethrough, a wire passing around the lens and seated in said groove and having one end anchored to said support, and the opposite end passed through said hole. 100
13. In a device of the character described, a lens having a circumferential edge groove, a support for the lens, said support having a post having a hole therethrough, a wire passing around the lens and seated in said groove and having one end anchored to said support, and the opposite end passed through said hole. 105
14. In a device of the character described, a lens having a circumferential edge groove, a support for the lens, said support having a post having a hole therethrough, a wire passing around the lens and seated in said groove and having one end anchored to said support, and the opposite end passed through said hole. 110
15. In a device of the character described, a lens having a circumferential edge groove, a support for the lens, said support having a post having a hole therethrough, a wire passing around the lens and seated in said groove and having one end anchored to said support, and the opposite end passed through said hole. 115
16. In a device of the character described, a lens having a circumferential edge groove, a support for the lens, said support having a post having a hole therethrough, a wire passing around the lens and seated in said groove and having one end anchored to said support, and the opposite end passed through said hole. 120
17. In a device of the character described, a lens having a circumferential edge groove, a support for the lens, said support having a post having a hole therethrough, a wire passing around the lens and seated in said groove and having one end anchored to said support, and the opposite end passed through said hole. 125
18. In a device of the character described, a lens having a circumferential edge groove, a support for the lens, said support having a post having a hole therethrough, a wire passing around the lens and seated in said groove and having one end anchored to said support, and the opposite end passed through said hole. 130

through said hole and bent at an angle at the outlet end of said hole, and a tension increasing member between the edge of the lens and the support.

5 11. In a device of the character described, a lens having a circumferential edge groove, a support for the lens, said support having a post having a hole therethrough, a wire passing around the lens and seated in said

10 groove and having one end anchored to said support, and the opposite end passed through said hole and bent at an angle at the outlet end of said hole, and a wedge member between the edge of the lens and the support.

15 12. In a device of the character described, a lens having a circumferential edge groove, a support for the lens, said support having a post having a hole therethrough, a wire 20 passing around the lens and seated in said groove and having one end anchored to said support and the opposite end passed through said hole and bent at an angle at the outlet end of said hole, and a wedge member inserted between the edge and the lens and the mount, and conforming to the edge of the lens.

25 13. In a device of the character described, a lens having a circumferential edge groove, a support for the lens, said support having a post having a hole therethrough, a wire 30 passing around the lens and seated in said groove and having one end anchored to said support and the opposite end passed through said hole and bent at an angle at the outlet end of said hole, and a wedge member inserted between the edge of the lens and the mount and held in place by the tension on the wire.

35 14. In a device of the character described, 40 a lens having a circumferential edge groove,

a support for the lens, said support having a projecting post, a wire passing around the lens and seated in said groove, and having one end anchored to said support, and a fastening 45 securing the other end of said wire to said support, said fastening including an opening through said support together with additional means on the post for securing said other end directly to said projecting 50 post, and a tension-increasing member between the edge of the lens and the support.

15 15. In a device of the character described, a lens having a circumferential edge groove, a support for the lens, said support having 55 a projecting post, a wire passing around the lens and seated in said groove, and having one end anchored to said support, and a fastening securing the other end of said wire to said support, said fastening including an 60 opening through said support together with means securing said end to said projecting post, and a longitudinal slot in the support in which slot the wire lies.

16. In a device of the character described, 65 a lens having a circumferential edge groove, a support for the lens, said support having a projecting post, a wire passing around the lens and seated in said groove, and having one end anchored to said support, and a 70 fastening securing the other end of said wire to said support, said fastening including an opening through said projecting post through which opening the wire is passed and secured.

75 In testimony whereof I have hereunto signed my name in the presence of two subscribing witnesses.

GERARDUS POST HERRICK.

Witnesses:

Copies of this patent may be obtained for five cents each, by addressing the "Commissioner of Patents,
Washington, D. C."

It is hereby certified that in Letters Patent No. 1,317,131, granted September 23, 1919, upon the application of Gerardus Post Herrick, of New York, N. Y., for an improvement in "Lens-Mountings," an error appears in the printed specification requiring correction as follows: Page 4, line 123, claim 9, for the word "recessed" read *secured*; and that the said Letters Patent should be read with this correction therein that the same may conform to the record of the case in the Patent Office.

Signed and sealed this 14th day of October, A. D., 1919.

[SEAL.]

M. H. COULSTON,

Acting Commissioner of Patents.

Cl. 88—47.
